NONEXTRUDING ASPHALT JOINT

Filed Aug. 14, 1935

UNITED STATES PATENT OFFICE

2,049,138

NONEXTRUDING ASPHALT JOINT

Robert R. Robertson, Chicago, Ill., assignor to
 The Translode Joint Company, Chicago, Ill., a
 corporation of Illinois

Application August 14, 1935, Serial No. 36,111

17 Claims. (Cl. 94—18)

The present invention relates to a concrete road joint and more particularly to a load transmission expansion joint wherein a base unit is provided to support a non-extruding asphalt core unit embodying the principal features of this invention and including a preformed asphalt filler provided with a series of apertures whereby the filler, upon expansion of the road slabs is adapted to be readily compressed allowing the 10 filler material to fill in the openings and also extend into longitudinal and vertical grooves provided in groove forming plates clamped against the sides of the apertured portions of the asphalt filler to form upper and end stop shoulders 15 on the filler to obviate leakage into the joint.

It is an object of this invention to provide an expansion joint for roads and the like, said joint including in combination a base unit and a core unit supported thereby, said core unit including 20 an apertured preformed plastic filler having groove forming plate members secured on opposite sides thereof, said base unit, the plastic filler and the groove forming plates adapted to be embedded in concrete, and said filler adapted when compressed, by the expansion of the concrete, to flow into the filler apertures and into the grooves formed by said plates to provide a non-extruding type of road joint filler mechanism.

It is also an object of this invention to provide 25 an expansion joint road forming mechanism including a non-extruding apertured plastic filler and means engaged on the sides of the filler to provide grooves for receiving parts of the filler when the same is compressed due to the expansion 30 of the road slabs between which the joint is formed.

It is also an object of this invention to provide 35 a concrete joint forming device including a plastic core having groove forming means seated on each side thereof, said plastic core being provided with apertures the size and number of which are determined by the maximum degree of compression for which the core is designed.

It is a further object of this invention to provide 40 a concrete expansion joint mechanism including a base on which is supported a non-extruding beaded plastic filler having openings provided at intervals therein and adapted to be filled by the material forming the filler when 45 said filler is compressed between concrete slabs.

It is an important object of this invention to provide 50 an expansion joint mechanism for embedding in concrete to separate concrete road slabs, said mechanism comprising a base for

supporting groove forming plates on opposite sides of a preformed plastic filler having a plurality of openings punched therein whereby when the joint mechanism is embedded between concrete road slabs said preformed plastic filler 5 forms a non-extruding core which is compressible with the expansion of the road slabs and is prevented from extruding from the joint due to the fact that the material forming the plastic filler is permitted to fill in the openings provided 10 therein for the purpose.

Other and further important objects of this invention will be apparent from the disclosures in the specification and the accompanying drawing.

This invention (in a preferred form) is illustrated in the drawing and hereinafter more fully described.

On the drawing:

Figure 1 is a transverse vertical fragmentary 20 section taken through an expansion joint mechanism embedded between concrete road slabs and including an improved apertured preformed plastic filler having groove forming plates contacting opposite sides thereof.

Figure 2 is a similar sectional view with the 25 filler cap removed and illustrating the position of the parts when the concrete road slabs have expanded to compress the plastic filler causing the filler material to extrude into the apertures 30 and grooves, said view also indicating in dotted lines the separation of the concrete slabs from the plates and core upon the contraction of the road slabs.

Figure 3 is a fragmentary side elevation of the 35 preformed plastic filler removed from the joint and illustrating the cuts in the filler covering.

Figure 4 is a fragmentary side view of the plastic 40 filler showing the groove forming plate in position and partly broken away to illustrate the resultant plastic beads or shoulders and the filled 45 in apertures in dotted lines.

Figure 5 is a fragmentary vertical sectional view taken through a concrete road section, the slabs of which are separated by a modified form of expansion joint mechanism including the preformed apertured plastic filler and the groove forming plates on opposite sides thereof.

Figure 6 is an enlarged fragmentary sectional view of the plastic filler and the groove forming 50 plates with the paper coverings of the filler exaggerated and showing the cuts for permitting the extruding of the material when the filler is compressed.

Figure 7 is a vertical sectional view of a mod- 55

ified form of preformed plastic filler having preformed ribs or beads integrally cast on the sides thereof to which the groove forming plates are secured.

5 Figure 8 is a similar fragmentary view of a filler having modified forms of plates on the sides thereof carrying preformed plastic bars or heads for contacting the sides of the filler.

As shown on the drawing:

10 Figures 1 and 2 illustrate a vertical sectional view of an improved road expansion joint forming mechanism which is embedded between concrete road slabs 1 which are supported upon the road sub-grade in the regular manner. In the 15 form of the device illustrated in Figures 1 to 4 inclusive, the expansion joint is of the load transmission type including a load transmission base unit which serves as a load transmitting medium between the adjacent slabs of the concrete road. 20 In the present showing, the base unit comprises an elongated base member consisting of a solid base plate 2 constructed of sheet metal or other suitable material. The longitudinal margins of the base plate 2 are bent upwardly and then inwardly toward one another to form oppositely positioned guide channels 3. The guide channels 3 of the base unit provide oppositely positioned guide grooves 4. The margins of the top plates of the guide channels 3 are bent upwardly and 30 are cut away to provide spaced upwardly projecting retaining flanges 5. The retaining flanges 5 on opposite sides of the base unit are staggered with respect to one another. Notches are provided between the retaining flanges 5 on each 35 side of the base unit to permit load transmitting anchor shoes or holders to be seated therein in proper spaced relation for the support of a core unit hereinafter more fully described.

The load transmitting mechanism associated 40 with the base unit consists of a plurality of anchor shoes or holders which are movably or shiftably engaged in the base section and are arranged longitudinally in offset or staggered relation with respect to one another. The anchor shoes or 45 holders are of substantially identical construction and are arranged with the adjacent shoes reversed with respect to one another as clearly illustrated in Figure 1. Each of the anchor shoes is constructed of metal and comprises an angle 50 bar including a base flange 6 and an upright flange or web 7 integral with said base flange. Struck outwardly from the upper margin of each 55 of the flanges or webs 7 are anchoring blades or wings 8 leaving the inner side of the upright flange or web flat.

Supported on the base flanges 6 of the anchor shoes between the upright flanges or webs 7 is a preformed plastic filler or core board 9 constructed of asphalt or other suitable material. The preformed filler board 9, as clearly illustrated in 60 Figure 3 is provided with longitudinally directed staggered rows of apertures or openings 10 which may be of different sizes as illustrated, if desired. The apertures or openings 10 are provided in the 65 preformed plastic filler 9 for the purpose of providing sufficient space into which the material forming the filler may be squeezed when the plastic filler or core is compressed due to the expansion of the road slabs 1. The size and number 70 of the apertures are regulated or determined by the degree of compression to which the core board 9 is designed to be subjected to, so that the maximum amount of compression may be applied to the core board without causing extrusion of the 75 plastic material from the joint.

Secured to opposite sides of the plastic core board 9 are layers of paper or cover sheets 11, each provided with an upper longitudinal slit or cut 12 and with two vertical side slits or cuts 13 to afford weakened portions to facilitate extrusion of the plastic material when the core board is compressed. 5

Engaged against each side of the apertured portion of the preformed plastic filler 9 is a groove forming frame in the form of a metal plate 14, 10 the upper longitudinal portion and the end margins of which are deflected outwardly to form mouldings 15, the edges of which are deflected inwardly toward the filler to form the flanges 16. Before the concrete is poured the groove forming 15 frames are projected downwardly between the side surfaces of the core board 9 and the straight surfaces of the upright flanges or webs 7 of the anchor shoes, thereby holding the edges of the top flange 16 against the sides of the plastic filler to provide top and side grooves 17. Since the groove forming frames are positioned on opposite sides of the preformed plastic filler or core board 9 the grooves 17 are formed on opposite sides of the filler as clearly illustrated in Figure 1 with 25 said grooves 17 communicating with certain of the apertures 10 of the plastic filler board 9.

Before the pouring of the concrete to form the road slabs 1, a cap 18 is removably engaged over the upper margin of the plastic filler board 9. 30 Engaged within the cap 18 is a supporting pad or bar 19 which forms a part of the cap and rests upon the top edge of the filler board 9 to hold the removable cap 18 in a set position of adjustment. The cap 18 together with the bar 35 19 are removed after the pouring of concrete to provide a groove in the concrete between the road slabs 1 above the plastic filler board 9. The groove is partly filled with asphalt or the like to form a top filler 20. 40

When the concrete road slabs 1 are subjected to temperature increases, they expand toward one another thereby compressing the joint core unit and primarily the asphalt filler board or plate 9 causing the material of the preformed asphalt 45 filler to move or flow into the apertures or openings 10 and into the grooves 17 formed in the concrete slabs 1 by the mouldings 15 of the side plates 14. With the compression taking place as described, the asphalt filler fills the apertures 10 50 and the grooves 17, and assumes the compressed form illustrated in Figure 2. The asphalt extruding through the slits or cracks 12 and 13 of the side coverings of the core board 9 fills the grooves 17 to form the plastic top and end mouldings 21 55 (Figure 4) which serve as top and end shoulders to prevent leakage into the joint. The apertured core board 9 is thus compressed into a solid board having the stop shoulders or mouldings 21 60 integrally formed on the sides thereof. 60

After the compression of the plastic core board 9 into the shape illustrated in Figure 2, the concrete slabs upon contraction, due to a reduction in the temperature thereof, pull away from opposite sides of the compressed core unit into approximately the positions illustrated in dotted lines in Figure 2, with the concrete separating from the metal frame plates 14 and 15, leaving said plates adhering to the sides of the plastic core. Attention is called to the fact that when 70 the concrete slabs contract and separate, that the portions of the slabs adjacent the frame flanges 16 do not move out of contact therewith and thus form stops for a filling which may be poured into the marginal spaces extending from 75

the top and ends of the joint inwardly to said stop flanges 16.

Figure 5 illustrates a modified form of non-extruding expansion joint embedded between concrete road slabs 1 and resting upon the subgrade of a road in the customary manner. The modified form of expansion joint comprises a base plate 22 constructed of sheet metal or other suitable material. The longitudinal margins of the base plate 22 are bent upwardly and then inwardly toward one another to form oppositely positioned guide channels 23. Slidably engaged in the guide channels 23 are a pair of base flanges 24 which are integrally formed on the lower edges of a pair of base plates 25. The upper margins of the base plates 25 are deflected outwardly to provide the inclined walls 26 having the upper margins thereof deflected inwardly toward one another to form the top flanges 27 thereby forming mouldings providing recesses or grooves 28. Engaged downwardly between the plates 25 is a preformed plastic filler or board 29 constructed of asphalt or other suitable material similar to the board illustrated in Figure 3. The asphalt filler is punched out at intervals to provide a series of apertures or openings 30 which are closed by means of the plates 25 and the upper groove forming portions 26 of said plates. With the expansion of the road slab 1 due to temperature changes, the slabs move toward one another and compress the preformed plastic filler 29 causing the material to flow into the openings 30 and into the grooves 28 similar to the arrangement illustrated in Figure 2. The provision of the grooves 28 in the concrete slabs 1 and the provision of the openings 30 in the preformed plastic filler 29 produces a non-extruding asphalt expansion joint between the road slabs 1 for the reason that sufficient areas are provided for the reception of the material forming part of the plastic filler when the same is compressed by the expansion of the road slabs.

Figure 7 illustrates a modified form of pre-formed plastic core unit comprising a plastic board 31 provided with apertures 32 and having integrally formed on the sides thereof plastic beads or bars 33. The beads 33 and the sides of the board 31 are covered with a paper covering 34. Positioned against the sides of the board 31 are metal plates 35 having outwardly deflected portions 36 terminating in straight flanges 37 which contact the beads 33 and may be secured thereto by nails or the like. The plate portions 36 and 37 provide grooves 38 for the reception of plastic material from the board 31 when the same is compressed between concrete road slabs. The material filling the grooves 38 forms stop mouldings similar to the mouldings 21 illustrated in Figure 4.

Figure 8 illustrates a fragmentary portion of another modified form of core unit comprising a preformed apertured plastic core board the same as illustrated in Figures 1 and 3. Positioned on opposite sides of the core board are groove forming metal plates similar to those shown in Figure 7. In this modified form preformed plastic beads or bars 39 are secured to the inner sides of the plate flanges 37, by nails or other suitable means, and are positioned to contact against the covered sides of the board prior to the pouring of concrete to form the road slabs.

It will of course be understood that various details of construction may be varied through a wide range without departing from the principles of this invention and it is therefore not the pur-

pose to limit the patent granted hereon otherwise than necessitated by the scope of the appended claims.

I claim as my invention:

1. An expansion joint forming mechanism comprising a base, a preformed filler of compressible material supported on the base and having a plurality of openings therein, and groove forming plate members positioned on opposite sides of the apertured portion of said compressible filler. 5

2. An expansion joint forming mechanism comprising a base, a preformed filler of compressible material supported on the base and having a plurality of openings therein, groove forming plates positioned against opposite sides of the apertured portion of said filler, and a cap removably engaged over the upper edge of the filler. 10

3. An expansion joint forming mechanism comprising a base, a preformed filler of compressible material supported on the base and having a plurality of openings therethrough and slits in the side surfaces thereof, and groove forming plate members contacting the opposite sides of the filler. 20

4. An expansion joint forming mechanism comprising a base, a preformed plastic filler board supported by the base, coverings on the side surfaces of the filler board having slits therein, said filler board and the coverings thereof having 30 registering openings therein, and grooved frame members on opposite sides of the filler board and contacting said coverings to substantially enclose the openings and the slits in said coverings. 35

5. A non-extruding asphalt road joint including in combination a pair of oppositely positioned concrete road slabs, an expansion joint base embedded in the slabs, a preformed asphalt filler board supported on the base between said slabs 40 and having openings and slits therein, groove forming frame plates supported against opposite sides of the filler board and embedded in said slabs, and a groove forming cap removably engaged on the top of said filler board between said 45 slabs.

6. A non-extruding asphalt road joint including in combination a pair of oppositely positioned concrete road slabs, an expansion joint base embedded in the slabs, load transmission members 50 embedded in said slabs and movably engaged in said base, a preformed plastic filler board supported between the load transmission members and between said slabs, said filler board having openings therein and slits cut in the side surfaces 55 thereof, groove forming plates supported between the load transmission members and said filler board and partly embedded in the road slabs, and a cap removably engaged on the filler board. 60

7. A non-extruding asphalt joint for embedding in concrete and comprising a load transmission base, and a preformed plastic filler board supported thereby and having openings therein arranged to be filled by the plastic material of 65 the filler board to obviate extrusion of the plastic material from the concrete when due to temperature increases the concrete expands and compresses the filler board.

8. A non-extruding asphalt joint embedded in 70 concrete and comprising a base, a preformed asphalt filler board on the base and embedded in the concrete, and side coverings on the filler board, said filler board and side coverings having registering openings therein. 75

9. A non-extruding asphalt joint including in combination a core unit comprising a preformed plastic board having openings therein, and coverings on the sides of the board having openings 5 therein registering with the openings in said board, said coverings having weakened portions provided therein.
10. A non-extruding asphalt joint for embedding in concrete and comprising a base, a pre-formed plastic filler board thereon having openings therein, coverings on the sides of the board also having openings therein registering with the 10 openings in the board, and plate members embedded in the concrete on opposite sides of the board for closing said openings, said plate members having mould portions for forming frame-like grooves in the concrete communicating with the openings, said coverings having weakened portions adjacent the grooves whereby said board 15 when compressed by the expansion of the concrete extrudes into the openings and out through said weakened portions of the coverings to fill the grooves and form stop beads on the sides of the compressed board.
11. A non-extruding asphalt joint for embedding in concrete and including in combination a core unit comprising a preformed plastic filler board having openings therein to be filled by the material forming the board when the board is 20 compressed due to the expansion of the concrete, and grooved plates on the sides of the board having the grooves thereof facing the board to be filled by material from the board to integrally form stop mouldings on the sides of the board.
12. A non-extruding asphalt joint for embedding in concrete and including in combination a core unit comprising a preformed plastic filler board having openings therein, plastic ribs integrally formed on the sides of the board above 25 the openings, and groove forming plates positioned against the sides of the board and secured to said ribs.
13. A joint forming mechanism including in combination a core unit comprising a preformed plastic filler board having openings therein, groove forming plates positioned against the sides of the board, and plastic bars secured to the plates and contacting the board. 30
14. A joint forming mechanism including in combination a core unit comprising a preformed plastic filler board having openings therein, and means for forming intersecting stop mouldings on both sides of the board, when the board is compressed. 35
15. A joint forming mechanism including in combination a core unit comprising a plastic filler board, plates positioned adjacent the sides of the board, and bar members projecting beyond the sides of the plates for holding portions of said plates spaced from the board to form spaces between the plates and said board. 40
16. A joint forming mechanism including in combination a core unit comprising a plastic filler board, and coverings on the sides of the board having slits therein for the extrusion of the material forming the board when said board is compressed. 45
17. A non-extruding asphalt joint for embedding between concrete slabs and including a core unit comprising a preformed plastic filler board having slits in the side surfaces thereof, and plates on the sides of the board having grooves formed therein and covering said slits to be filled by the material forming the board to form stop mouldings on the sides of the board when the board is compressed due to the expansion of the concrete slabs. 50

ROBERT R. ROBERTSON.
